US00D777204S

(12) **United States Design Patent** (10) **Patent No.:** **US D777,204 S**
(45) **Date of Patent:** **** Jan. 24, 2017**

(54) **DISPLAY SCREEN OR PORTION THEREOF
WITH GRAPHICAL USER INTERFACE**

(71) Applicant: **Samsung Electronics Co., Ltd.**,
Suwon-Si, Gyeonggi-Do (KR)

(72) Inventors: **Min Sun Lee**, Seoul (KR); **Olivia Lee**,
Seoul (KR); **Han Chul Jung**,
Seongnam-si (KR)

(73) Assignee: **Samsung Electronics Co., Ltd.**,
Gyeonggi-do (KR)

(**) Term: **14 Years**

(21) Appl. No.: **29/498,993**

(22) Filed: **Aug. 11, 2014**

(30) **Foreign Application Priority Data**

Feb. 11, 2014 (KR) 30-2014-0006881

(51) **LOC (10) Cl.** **14-04**

(52) **U.S. Cl.**
USPC **D14/489**

(57)

CLAIM

The ornamental design for a display screen or portion thereof with graphical user interface, as shown and described.

DESCRIPTION

The single FIGURE is the front view for a display screen or portion thereof with graphical user interface showing our new design.

The broken lines illustrate the display screen or portion thereof and form no part of the claimed design.

1 Claim, 1 Drawing Sheet
